UNITED STATES PATENT OFFICE.

TOMLINSON FORT JOHNSON, JR., OF ATLANTA, GEORGIA.

THROW-OFF OR CIRCUIT-BREAKING SWITCH FOR SKEET HEADS.

Application filed May 13, 1920, Serial No. 381,135. Renewed May 2, 1923.

To all whom it may concern:

Be it known that I, TOMLINSON F. JOHNSON, Jr., a citizen of the United States, residing at Atlanta, in the county of Fulton and State of Georgia, have invented a new and useful Throw-Off or Circuit-Breaking Switch for Skeet Heads, of which the following is a specification.

This invention refers to throw-off or circuit breaking switches particularly adapted for use on high tension transmission lines for maintaining the continuity of the circuit under normal conditions but causing the breaking of the circuit on the passage of abnormally high tension or heavy currents to thereby protect translating devices fed by the transmission line or lines.

The object of the invention is to provide an electro-magnetic device which, under normal conditions, maintains the circuit closed but, on the passage of an abnormal current liable to do injury to the translating devices, the circuit is ruptured and can only be restored by an attendant.

The invention is susceptible of many different embodiments of which but one is shown.

In accordance with the invention the transmission line is assumed to feed translating devices in the form of transformers. The transmission line is assumed to be an overhead line and the circuit breaker or skeet head is mounted on top of the transformer from which latter rises a post or column which may be a column of insulating material through which a branch of the main line conductor passes to the transformer. By the term "skeet head" is meant a structure, such as defined in this case for breaking the circuit, because of the peculiar tone then emitted, simulating the high pitch tone of a mosquito. This term has become known commercially by such name, which has become recognized in the commercial art where the structure is in use. The circuit breaker is mounted on top of the column of insulating material and includes a spring actuated circuit breaker under the control of an electro-magnetic release responsive to abnormal currents, so that on an abnormal rise in electrical pressure the circuit is ruptured and the translating device fed thereby is thus protected.

The invention is intended for high tension long distance transmission lines where the voltage may reach from 60,000 to 110,000

volts, or even higher, but should a super-high tension be imposed upon the main line the electro-magnetic device will be energized and the circuit to the transformer will be broken, thus protecting the latter. The circuit remains broken until purposely restored by an attendant.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

In the drawings:

Fig. 1 is a more or less diagrammatic view of the installation equipped with the invention.

Fig. 2 is a detailed view on a larger scale than Fig. 1, and also partly in section, showing a skeet head arrangement.

Fig. 3 is a view similar to Fig. 2 except that the locking means in the branch conductor from the main conductor is shown in the thrown position.

Referring to the drawings there is shown in Fig. 1 a main line conductor 1 which may be considered as terminating at a pole 2 to which the main line conductor is mechanically connected through a string of insulators 3, such arrangement being the usual practice.

Connected to the main line conductor 1 is a branch conductor 4 of a flexible nature passing over a roller 5 mounted in a block 6 fast on and supported by the conductor 1. The branch conductor 4 is mechanically and directly connected to the conductor 1 by clips 7. At the end of the conductor 4 remote from the clips 7 is a terminal 8.

There is also provided an electrical transformer 9 of suitable type, with a cap 10 from which rises a post 11 which may be formed of a series of nested and connected insulators 12 of a character common in high tension electric transmission lines. Usually the transmission systems are made up of a plurality of transmission conductors 1, with an equal number of transformers 9, but, as this particular arrangement is not material to the invention, but one transmission line

1 and one transformer 9 are shown in the drawings.

On top of post 11 there is an insulating member 13 carried by a conducting collar 14 on the uppermost one of the insulators 12. Rising from the insulating member 13 there is a fork or yoke 15 from one side of which there projects a shelf or bracket 16 on which there is mounted an electro-magnet 17. The 10 electro-magnet is provided with an armature carried by an arm 18 pivotally connected to one leg of the yoke 15, the arm 18 being under the influence of a spring 19 tending to move it away from the magnet 17.

15 Formed through the terminal portions of the legs of the yoke 15 are alined passages 20 indicated in dotted lines. Adapted to the passages 20 is a rod or bar 21 long enough to span the space between the legs 20 of the yoke and enter both passages and also to project for an appropriate distance beyond that side of the yoke carrying the armature arm 18. Mounted on the rod 21 is a sleeve 22 made fast to the rod by a 25 lock nut 23 and extending into the sleeve 22 is an expansion spring 24 of a length to reach to an adjacent leg of the yoke 15, with the spring sufficiently open when un-compressed to force the sleeve 22 away from the yoke 15, thereby carrying the rod 21 from traversing relation to the yoke 15. The armature arm 18 is in the nature of a latch, being provided with a nose 25 adapted to engage a coacting member 26 on the 35 sleeve 22.

When the parts are properly set current from the main line 1 passes by way of the conductor 4 and terminal 8 to the rod 21 and thus by way of the yoke 15 through 40 the interior of the column 11 to the transformer 9, this last named arrangement being common to installations of the character to which the invention relates and hence needs no special illustration or description.

45 The electro-magnet 17 is fed by conductors 27, 28, one being connected to the yoke 15 and the other to the collar 14, forming a path which may be in series to the main course of current through the device to the 50 transformer 9.

When the parts are properly set and current is passing, the energy developed by the magnet 17 is insufficient to draw the armature arm 18 toward the magnet 17 so that 55 the member 26 is held by the nose 25 in such manner as to maintain the rod 21 in holding relation to the terminal 8. If, now, an abnormal current should occur on the main line it will pass through the transformer 9, but before any harm can come to the transformer the super-current passing through the electro-magnet 17 causes the 60 movement of the latch nose 25 out of the path of the companion member 26, thereby 65 releasing the spring 24 to action and caus-

ing it to move the rod 21 to a sufficient extent to release the terminal 8.

The conductor 4 is under a normal strain because of the presence of the weight 29 pendantsly carried by a roller 30 sustained 70 by a portion of the conductor 4 between the clips 7 and the roller 5. As soon as the terminal 8 is released the weight 29 acts to move the terminal 8 toward the block 6 well away from the skeet head and far beyond 75 flashing distance from the rod 21, wherefore, when the circuit breaker is opened there is no possibility of producing an arc.

This invention has features in common 80 with my application No. 381,134, for a throw-off circuit breaking switch for skeet heads, filed May 13, 1920; and my application 85 No. 361,526, for automatic circuit breaker attachment for high tension electric installation, filed February 26, 1920.

What is claimed is:

1. The herein described circuit breaking means for installation between an overhead high tension transmission line and a translating device located at a lower level, comprising a terminal adapted to be suspended from the transmission line by a flexible conductor, a slidable rod having a normal tendency in one direction and adapted to 90 engage said terminal, a support for the rod, and an electro-magnetically operated means for holding the rod in opposition to its normal tendency and responsive to abnormal currents on the transmission line to cause the 95 release of the rod and the consequent escape of the terminal to thereby cause the breaking of the circuit.

2. The herein described circuit breaking means for installation between an overhead high tension transmission line and a translating device, comprising a terminal adapted to be suspended from a flexible conductor, a slidable member adapted to be carried by the translating device and provided with means for imparting to it a normal tendency to move in one direction, said terminal being constructed to be traversed by the said slidable member, and an electro-magnetically operated latch for holding the slidable member against its normal tendency thereby holding said terminal in position to maintain the circuit closed, said electro-magnetically operated latch being inoperative to normal currents and responsive to 105 abnormal currents on the line.

3. The herein described circuit breaking means for installation between a high tension transmission line and a translating device, comprising a yoke adapted to be mounted on the translating device and provided with legs for inclusion in the circuit thereto, a rod adapted to traverse the legs of the yoke, a terminal adapted to be carried by a 110 flexible conductor and constructed to be 115 flexible conductor and constructed to be 120

traversed by said rod, electro-magnetic means carried by the yoke and supplied with current from the main line through the flexible conductor, means for imparting to the rod a normal tendency to move toward one position to release the terminal, and a latch responsive to energy developed in the

electro-magnetic means on the passage of an abnormal current therethrough to release the rod to its normal tendency.

10

In testimony, that I claim the foregoing as my own, I have hereto affixed my signature.

TOMLINSON FORT JOHNSON, JR.
